INKWELL

Roy Eugene Stroh, Brookline, Pa., assignor to The Turner and Harrison Steel Pen Manufacturing Company, Philadelphia, Pa., a corporation of Pennsylvania

Application February 3, 1944, Serial No. 520,860

9 Claims. (Cl. 120—69)

This invention relates to ink wells, and has reference more particularly to ink wells of the type having small pen dip reservoirs which are replenishable as the ink supply in them is used up, from larger storage reservoirs within the wells.

The chief aim of my invention is to provide an ink well of the kind referred to which can be economically produced in quantity from relatively inexpensive materials; which is devoid of movable parts, small or restricted passages, and/or rough surfaces in the crevices in which ink would be likely to collect and dry; and which is resistive to easy upsetting.

In connection with an ink well having the foregoing attributes, I further aim to make improved provisions which will insure against ink spillage incident to replenishment of the supply in the dipping reservoir from the storage reservoir, as well as improved incorporated gauge provisions whereby the amount of ink in the storage can be readily and quickly ascertained at any time without necessitating the aid of any auxiliary measuring means.

Other objects and attendant advantages will appear from the following detailed description of the attached drawings, wherein

Fig. 1 is a perspective view of an ink well conveniently embodying my invention.

Fig. 2 is a vertical longitudinal sectional view of the well taken as indicated by the angled arrows II—II in Fig. 3, which is a horizontal section of the well taken as indicated by the angled arrows III—III in Fig. 2.

Fig. 4 is a transverse sectional view of the well taken as indicated by the angled arrows IV—IV in Figs. 2 and 3.

Fig. 5 is a view corresponding to Fig. 2 showing the well swung up on edge for the purpose of gauging the ink contents; and

Fig. 6 is likewise a view corresponding to Fig. 2 showing how the well is tipped to enable replenishing of the supply in the dip reservoir 23 from time to time from the main reservoir.

As herein exemplified, the body of my improved ink well is of relatively flat elongate oblong configuration and formed in two sections which are comprehensively designated respectively by the numerals 10 and 11.

The upper section 10 provides a top wall 12 which is arched both longitudinally and transversely of the body, front and rear side walls 13, 14, and end walls 15, 16, said side and end walls merging with the top wall through relatively sharp fillet curvatures as at 17. Centrally of the

length of the well, the upper section 10 is formed somewhat rearward of the longitudinal center of the well with a boss 18 whereof the axis is downwardly inclined slightly to the vertical toward the rear wall 14, said boss having an opening 19 which is tapered in part for reception and restraint of a pen holder such as partly indicated at P in Fig. 4. As shown, the boss 18 provides a lip 20 around the top of the opening 19 and projects to a considerable extent downward from the top wall 12 of the section 10 to serve as a baffle. At the front, the pendent portion of the boss 18 is cut away or recessed as at 21 for a purpose presently explained.

15 The lower section 11 of the well body is in the form of a flat plate which fits into a perimetric shouldered recess 22 in the bottom edge of the upper section 10. Below the pen-receiving opening the lower section 11 of the body provides a small auxiliary or pen dip reservoir 23 which is defined by end walls 25 and 26 of which the former is somewhat lower in height than the latter, and by front and rear side walls 27 and 28 which extend from the end wall 26 to a point well beyond the wall 25 and terminate somewhat short of the end wall 15 of the upper section 10 of the body, with resultant provision of an approach channel 29 to said dip reservoir from the main portion 30 of the interior of the well which 25 constitutes a storage reservoir for the ink supply. The walls 25—28 of the dip reservoir 23 and the channel 29 are all preferably integrally formed with the bottom section 11, the end wall 26 reaching very close to the top wall 12 of the upper 30 section 10. As shown in Figs. 2 and 4 all portions of the surface of the lower section 11 slope toward the bottom of the channel 29 which rises through a slope 31 to the upper edge of the wall 25. It will be particularly noted that the baffle 18 around the pen-receiving opening 19 extends down into the dip reservoir 23 to a level well below the top edge of the high end wall 26. In practice I prefer to mold the upper section 10 of the well body from opaque plastic material, and 35 the lower section 11 from transparent plastic material, to the top surface of which I attach a transversely arched strip 32 of light-colored material longitudinally of the well rightward of the dip reservoir 23. Thus upon tilting the well on 40 edge as shown in Fig. 5 the strip 32, by contrast with the ink, will serve as a gauge to show the ink level in the main or storage reservoir portion 30. If desired, the strip 32 may be graduated as indicated at 33 in Figs. 3 and 5. As an 45 alternative, I may construct the lower section 11

of opaque material except for a relatively small transparent area in the region of the gauge bar 32. After assembling, the two component sections 10 and 11 of the well body may be permanently united by cementing, or, if the character of the material from which the sections are constructed permits, they may be permanently secured by fusion along the regions of mutual abutment.

For use, the well is initially filled by way of the opening 19 to the level indicated by the dot-and-dash line L in Fig. 2, i. e., about even with the top edge of the wall 25 of the dip reservoir 23, the air from the interior being incidentally allowed to escape through a vent aperture provided at 35 (Figs. 1 and 4) immediately adjacent said opening behind the baffle 18 for that purpose. The vent aperture 35 is of a small diameter, as shown, so as to be negligible from the standpoint of allowing evaporation of the ink to take place. As the ink in the dip reservoir 23 recedes through use of the pen P, it may be replenished by tipping the well slightly after the manner shown in Fig. 6, with the result that ink trapped in the channel 29 from the main reservoir 30 will flow over the inclined surface 31 and over the low dam wall 25 into said dip reservoir, the opposite high end and high side walls 26 and 27, 28 of the latter acting as barriers to insure its retention. If the well is tipped beyond an angle greater than that of the slope 31, the excess delivered from the channel 29 will pass over the top of the high wall 26 of the dip reservoir 23 and return to the main or storage reservoir 30. During subsequent leveling of the well any ink in excess of the dip reservoir will flow over the top edge of the low wall 25 of the dip well 23 into the channel 29 and likewise find its way back into the main or storage reservoir 30. In the event that the well is erroneously tipped in the opposite direction, it is evident that the baffle 18 will act as a deflector to insure against spillage of ink through the pen opening 19. It will be further evident that the baffle 18 will also serve to preclude spillage in the event that the well is angularly tilted laterally in either direction. Due to sloping of all portions of the surface of the well bottom toward the channel 29 substantially all the ink in the main or storage reservoir 30 will be available for replenishing the supply in the dip reservoir 23 before the well need be refilled. The amount of stored ink can of course be ascertained at any time by standing the well on edge as shown in Fig. 5 when its level can be seen through the transparent bottom 11 by contrast with the light-colored gauge strip 32. Due to being shallow and flat, my improved ink well is obviously immune against easy upsetting.

The well may be cleaned when necessary by introducing water through the pen receiving opening 19, which after having accomplished the cleaning can be drained by laterally tipping the well about its front bottom corner edge, i. e., the edge at the left of Fig. 4, and finally completely inverting it. As this is done, the water will first be collected in the forward part of the well and finally as the well is turned upside-down, will be diverted by the baffle 18 to pass out through the pen opening 19 without attendant discharge of any of the water through the vent aperture.

I do not of course consider myself limited to the precise proportions or structural details of the well as herein shown, by way of example,

since these can be varied in practice without departing from the scope of my invention as defined in the appended claims.

Having thus described my invention, I claim:

- 5 1. An ink well having a hollow body whereof the interior is subdivided to afford a main or storage reservoir for the ink, and a smaller dip reservoir below a pen-receiving opening in the top wall of the body, defined by high and low end walls and side walls upstanding from the well bottom, said side walls extending from the high end wall substantially at the height of the latter past the low end wall to a point adjacent one end wall of the body to form an approach channel to said dip reservoir.
- 10 2. An ink well having a hollow body whereof the interior is subdivided to afford a main or storage reservoir for the ink, and a smaller dip reservoir below a pen-receiving opening in the top wall of the body, defined by high and low end walls and side walls upstanding from the well bottom, said side walls extending from the high end wall substantially at the height of the latter past the low end wall to a point adjacent one end wall of the body to form an approach channel to said dip reservoir; and said channel having a bottom with a portion which slopes upward to the top edge of the low wall of the dip reservoir.
- 15 3. An ink well according to claim 2, wherein the bottom of the approach channel extends to a level below that of the main or storage reservoir.
- 20 4. An ink well according to claim 2, wherein all portions of the bottom of the main or storage reservoir in the body slope toward the bottom of the approach channel.
- 25 5. An ink well according to claim 2, wherein the axis of the pen-receiving opening is inclined slightly to the vertical toward the rear side wall of the well body, and wherein a baffle around the rear of said opening reaches down from the top wall of the body into the dip reservoir to a level somewhat below the top of the front side wall of said dip reservoir.
- 30 6. An ink well according to claim 2, wherein the axis of the pen-receiving opening is inclined slightly to the vertical toward the rear side wall of the well body, wherein a baffle around the rear of said opening reaches down from the top wall of the body into the dip reservoir to a level somewhat below the top of the front side wall of said dip reservoir; and wherein a vent aperture in the top wall of the body behind the baffle serves to permit air displacement during filling of the well through said opening.
- 35 7. An ink well according to claim 2, wherein the top and side walls of the body are substantially opaque, and the bottom has a transparent portion, and wherein a strip of light-colored material fixed within the main or storage reservoir to the upper surface of the transparent portion of the bottom, serves, by contrast with the ink, as a level gauge when the well is turned up on edge.
- 40 8. An ink well according to claim 2, wherein the body is formed in two sections, one from opaque plastic material and providing the top and side walls of said body, and the other is formed at least in part from transparent plastic material and providing the bottom and the dip reservoir with its approach channel; wherein after assembling, the two sections are permanently united fluid-tight along the regions of mutual contact; and wherein a strip of light-

colored opaque material fixed within the main or storage reservoir at the transparent portion of the bottom serves, by contrast with the ink, as a level gauge when the well is turned up on edge.

9. An ink well according to claim 2, wherein the body is of elongate shallow configuration; wherein the pen-receiving opening is located cen-

trally of the length of the body somewhat to the rear of its longitudinal median; and wherein the dip reservoir is positioned to correspond with the pen-receiving opening with its approach channel extending in the direction of the length of said body.

ROY EUGENE STROH.
